United States Patent Office

Des. 198,784
Patented Aug. 4, 1964

198,784

VEHICLE SEAT

Chester J. Barecki, 901 Broadway Ave. NW,
Grand Rapids, Mich.

Filed Mar. 20, 1963, Ser. No. 74,066

Term of patent 14 years

(Cl. D15—8)

Fig. 1

Des. 198,784

PAGE 2

Fig. 2

FIGURE 1 is a front perspective view of a vehicle seat embodying my new design; and

FIGURE 2 is a rear perspective view thereof.

The end of the chair not shown is of conventional configuration. The dotted line showings are for illustrative purposes only.

I claim:

The ornamental design for a vehicle seat, substantially as shown and described.
